CLAIM

The ornamental design for a golf ball divot tool, as shown and described.

DESCRIPTION

FIG. 1 is a top plan view of a golf ball divot tool showing my design;

FIG. 2 is a top-right perspective view thereof;

FIG. 3 is a bottom-left perspective view thereof; and,

FIG. 4 is a left elevation view thereof, the right elevation view being a mirror image.

1 Claim, 4 Drawing Sheets
